A. L. PASCHALL,
ROTARY BEATER AND SEPARATOR.
APPLICATION FILED DEC. 8, 1915.

1,183,110.

Patented May 16, 1916.

UNITED STATES PATENT OFFICE.

ARMAND LYNNE PASCHALL, OF SPRINGFIELD, OHIO, ASSIGNOR TO THE BAUER BROTHERS COMPANY, OF SPRINGFIELD, OHIO, A CORPORATION OF OHIO.

ROTARY BEATER AND SEPARATOR.

1,183,110.

Specification of Letters Patent.

Patented May 16, 1916.

Application filed December 8, 1915. Serial No. 65,793.

To all whom it may concern:

Be it known that I, ARMAND LYNNE PASCHALL, a citizen of the United States, residing at Springfield, in the county of Clark 5 and State of Ohio, have invented certain new and useful Improvements in Rotary Beaters and Separators, of which the following is a specification.

This invention relates to improvements in 10 rotary beaters and separators more particularly designed for beating and separating the meats and hulls of cotton seed.

One of the objects of my invention is to provide an arrangement whereby the parts 15 may be made accessible for the purpose of repair or otherwise.

A further object is to so mount and support the revoluble screen cylinder and revoluble beater shaft as to permit the removal of certain of the parts without disturbing the bearings, which in the present case are shown as ball bearings.

A further object of the invention is to provide an improved rotary screen cylinder, so arranged that a portion thereof may be readily separated and removed from the machine so as to afford access to the interior of the cylinder.

A further object of the invention is to so construct the cylinder as to provide means to prevent the accumulation of material in the meshes of the screen.

In the accompanying drawings:—Figure 1 is a longitudinal sectional view of so much of a rotary beater and separator as is necessary to illustrate my improvements. Fig. 2 is a vertical section on the line 2—2 of Fig. 1 with the beater shaft omitted. Fig. 3 is an enlarged longitudinal section of some of the parts shown in Fig. 1. Fig. 4 is an end view of one of the divided bearings or housings for the beater shaft. Fig. 5 is an enlarged section of a portion of the construction shown in Fig. 2.

In the said drawings, 1 and 2 represent stationary end inclosing caps which are supported in any suitable manner from the base or frame of the machine, these caps not only serving to close the ends of the screen cylinder but also acting as supports for the cylinder and also for the beater shaft. The cylinder consists of a series of circular divided rings, 3, 4, 5 and 6 and longitudinally extending bars 7, 8, 9 and 10 to which the circular rings are connected; the rings and

bars serving to support the mesh portion or screen which is in two sections 11 and 12. As shown in detail in Fig. 5 the meeting edges of the screen sections are bent at right angles to the main portion and clamped between the longitudinally extending bars, which are formed in pairs, 7 and 8 constituting one pair and 9 and 10 the other. Each bar is of angle form and the respective members in each pair are placed back to back and bolted together with the screen sections between the same. As shown in Fig. 5 a space will thus be formed between the screen sections and the longitudinal bars equal to the thickness of the divided rings 70 so as to provide pockets 13, 14, 15 and 16. As the rotary screen revolves the material which is forced through the meshes of the screen will accumulate in these pockets and at a certain point in the revolution of the 75 screen the material will drop from the pockets in a mass and slide down the side of the screen and tend to dislodge any particles of material which have become clogged in the meshes.

Secured to one section only of the ring 3 is a worm gear 17 which is in mesh with a worm wheel 17^a driven from any suitable source of power. Secured to the end cap 1 is a circular track 18 which extends into the interior of the worm 17; ball bearings 19 being interposed between the track and the interior of the gear so as to provide a ball bearing support for that end of the reel. The opposite end of the reel has a ring 20 connected to one section only of the divided ring 6 and encircling this ring is a circular track 21 secured to the support 2, ball bearings 22 being interposed between the ring 20 and track 21 to provide a support for that end of the screen.

Extending longitudinally through the cylinder and supported at each end from the end caps 1 and 2 is a beater shaft 23 provided with a series of beater arms 24. Referring more particularly to the construction at the left hand side of the machine, it will be seen that the support 1 has an opening 25 about which is secured a two part bearing, the parts of which are represented by 26 and 27. Each of the parts of the bearing has a circular flange 28 at its inner end which is bolted to the support 1 and the respective parts of the bearing also have coinciding ears or flanges 29 to receive bolts for 110

securing the parts of the bearing together. The shaft 23 has a finished portion 30 which extends into the reduced portion 31 in the bearing members and then is provided with 5 a second reduced portion 32 and a third reduced portion 33 which project into the enlarged bore 34 of the bearing member and out the forward end of the same. Fitted in the space between the enlarged bore 34 and 10 the portion 32 of the shaft is a ball bearing of conventional form consisting of the races or rings 35 and 36 and balls 37, the ring 36 having a tight running fit with the shaft, but the ring 35 being inserted more or less 15 loosely in the bore 34 of the housing. Inserted into the enlarged bore of the housing member is a thrust collar or ring 38 which serves to take the thrust of the beater shaft through the ring 35; this collar or ring 38 20 having a flange 38^a on its outer end which is bolted to the flanges 39 on the outer ends of the bearing members. A driving pulley 40 is secured to the extreme outer end of the reduced portion 33 of the shaft, being held 25 in position thereon by the washer or collar 41 and bolt 42, and between the hub of the pulley and the inner ring or race 36 is inserted a sleeve 43, this sleeve serving to retain the ball bearings in position and also to 30 prevent endwise movement of the pulley.

The support 2 at the opposite end of the cylinder has an opening 44 about which is secured a divided housing 45 constructed in all respects like the housing at the opposite end of the cylinder in that it has circular flanges at its inner end which are secured to the support 2 and circular flanges at its outer end to which is bolted a cap 46 which serves to close the open end of the housing. 35 The shaft at that end of the cylinder is reduced and between this reduced portion of the shaft and the bore of the housing are inserted ball bearings composed of rings 47 and 48 and balls 49. The ring 47 is more or 40 less loosely fitted to the bore of the housing, the ring 48 has a running fit to the shaft. A washer or collar 50 secured to the end of the shaft by the nut 51, serves to hold the bearings in position.

50 As a result of this construction it will be seen that it is a simple matter to obtain access to the interior of the screen. This is accomplished by removing the bolts which connect the members of each pair of longitudinally extending bars 7, 8, 9 and 10 and then removing one section of the screen out through the top of the machine, this being permitted by reason of the fact that one sec-

tion of the ring 3 is disconnected from the gear 1 and that one section of the ring 6 is 60 disconnected from the bearing ring 20. It will be seen that in the event access is desired to the ball bearings at either end of the shaft 23, this can be readily had by disconnecting the housing from its support and 65 further disconnecting either the thrust ring 38 or cap 46, as the case may be, from the housing, the housing being then readily removed sidewise.

In addition to this, if it is desired to secure access to the end of the cylinder, this may be accomplished by further removing the pulley and thrust ring at the left hand end of the cylinder so that the cap 1 may be removed over the bearings without in any 70 way disturbing them in their relation to the shaft.

Having thus described my invention, I claim:

1. In a machine of the character described, a cylinder, stationary end supports for said cylinder, said end supports having openings, a revoluble shaft extending through said cylinder and openings, divided housings connected to said supports about 85 said openings capable of being separated laterally, and anti-friction bearings between said shaft and housing.

2. In a machine of the character described, a cylinder, stationary end supports for said cylinder, a revoluble shaft extending through said cylinder, one of said end supports having an opening through which said shaft extends, a divided housing removably connected to said support about 90 said openings, anti-friction devices between said shaft and housing but detachable from said housing, and a removable thrust collar connected with said housing and extending into the same.

3. In a machine of the character described, a cylinder, stationary end supports for said cylinder, a revoluble shaft extending through said cylinder and one of said end supports, a divided housing removably attached to said end support, anti-friction bearings having two races, one of which has a running fit to said shaft and the other a loose fit in said divided housing, and means for removably connecting said housing members to said support and to each other.

In testimony whereof, I have hereunto set my hand this 30th day of November, 1915.

ARMAND LYNNE PASCHALL.

Witness:

CHAS. I. WELCH.
